UNITED STATES PATENT OFFICE.

JOSEPH TAYLOR, OF OKLAHOMA, OKLAHOMA.

AUTOMATIC SPRINKLER-HEAD.

1,220,025.

Specification of Letters Patent. Patented Mar. 20, 1917.

Application filed October 25, 1916. Serial No. 127,629.

To all whom it may concern:

Be it known that I, JOSEPH TAYLOR, a citizen of the United States, residing at Oklahoma, in the county of Oklahoma and State 5 of Oklahoma have invented new and useful Improvements in Automatic Sprinkler-Heads, of which the following is a specification.

This invention is an improved automatic 10 sprinkler head adapted for use in connection with fire extinguishing systems, one object of the invention being to provide an improved sprinkler head of this character which is extremely strong and durable; 15 another object being to provide an improved automatic sprinkler head which embodies a pair of struts and a fusible link so constructed and arranged as to prevent strain from being applied to the fusible solder. 20 The invention consists in the features of construction, combination, and arrangement of devices, hereinafter fully described and claimed.

In the accompanying drawings:—

25 Figure 1 is a side elevation, partly in section, of an automatic sprinkler head constructed and arranged in accordance with my invention.

Fig. 2 is an elevation of the same at right 30 angles to Fig. 1 and showing the outer ends of the struts and of the fusible link.

Fig. 3 is partly a plain and partly a horizontal sectional view of the same.

Figs. 4 and 5 are detail perspective views 35 of the struts.

Figs. 6 and 7 are similar views of the members of the fusible link.

The head 1 comprises a diamond shaped frame 1 at the base of which is an exteriorly 40 threaded nipple 2 adapted to be screwed in the outer end of a water pipe. At the upper end of the frame is a cross bar 3 integral therewith and which has a threaded opening 4 which is concentric with and spaced 45 from the nipple.

A deflector 5 is provided with a threaded stem 6 which is engaged in and extends through the opening 4. A cap 7 is seated on the outer or upper end of the nipple and 50 forms a removable closure therefor.

To secure the closure cap in place, hold it thus secured under normal conditions, and cause the closure cap to be released in the event of a fire, I provide a pair of struts 55 8, 9, and also provide a fusible link 10. The strut 8 comprises an arm which has a wid-

ened outer end portion 11 provided in its upper side with a cross channel 12. On the under side of the strut 8 and at a point spaced from its outer end is a socket 13. 60 Near its inner end, on its upper side, the said strut is provided with a point 14 which engages in a circular depression in the lower or inner end of the screw 6. Said strut also has on its upper side a 65 downwardly extending wedge shaped point 15 which is spaced a greater distance from its inner end than the point 14.

The strut 9 has its outer end fitted as at 16 in the socket 13 of the strut 8. The 70 point 15 of the strut 8 engages in a groove 17 in the upper side and near the inner end of the strut 9 and said strut has at its end side, near its inner end a downwardly extending point 18 which engages in a central 75 depression in the upper side of the cap. Hence the two struts are angularly related to each other as shown. The points 14 and 18 of the struts are directly in line with the common axis of the screw 6 and 80 cap 7 and the point 15 between said struts is to one side of such common axis so that the downward pressure of the screw tends to turn the struts in opposite directions on the points 14, 15, and 18, as will be understood. The strut 9 is provided on its lower side near its inner end with a hook 19. The link 10, which is fusible, comprises a pair of members 20, 21, the member 20 is bent to form angularly related arms 22, 23, the 90 arm 22 having an opening 24 through which the outer end of the strut 8 extends so that that portion of the arm 22 which forms the upper side of the opening 24 bears in the cross channel 12 of said strut as shown. 95 The link member 21 has an opening 25 for the reception of the hook or lug 19. Said member bears on the upper side of the arm 23 of the link member 20 and is secured to said link member by fusible solder as at 100 26. Hence the fusible link serves to connect the outer ends of the struts together and utilizes the leverage of the struts so that the strain or stress on the link and the fusible solder is negligible. Hence the 105 sprinkler head is extremely strong and durable and there is no danger of the cap being released excepting in the event of a fire. Should a fire occur, the solder is melted, permitting the separation of the 110 members of the fusible link and owing to the pressure constantly maintained on the

inner ends of the struts by the screw and the arrangement of the pivoting point 15, to one side of the common plane or axis of the screw, cap, and points 14 18, the struts 5 as soon as they are released by the fusible link, separate and drop from between the cap and the screw, the cap is then removed from the seat by the pressure of the water on the wall discharged through the nipple 10 strikes the deflector and hence causes the water to be thoroughly sprinkled and the fire to be extinguished.

Owing to its shape, the frame of the sprinkler head is extremely strong as well 15 as being characteristic in appearance.

In practice, the sprinkler head with all of its parts excepting the fusible link is preferably made of high grade phosphor bronze metal but may be made of any suitable material.

Having described the invention, what is claimed is:

1. In a sprinkler head, a frame having a duct, a deflector spaced from the end of the 25 duct and having a stem extending from an opening in the frame and arranged opposite the end of the duct, a closure on the end of the duct, a pair of struts arranged at an angle to each other, one longer than 30 and extending beyond the other, said struts

being in mutual contact near their outer ends and being provided one with a recess on its under side near its outer end and the other with a projection on its outer end engaging in said recess, and one also having 35 a pointed portion near its inner end bearing on the inner end portion of the other, said struts bearing one against the inner end of the stem and the other against the closure, and a fusible link connecting the 40 outer portion of the struts together.

2. In a sprinkler head a closure cap, a stress applying member, a pair of struts in mutual contact at their inner ends and also at their outer ends, one of said struts having 45 a recess and the other having a projection engaging in said recess, one of said struts also having a hook at the outer end and the other having a hook at the outer side, spaced from the inner end, and a link 50 comprising a pair of members and fusible solder connecting said members together, the members being respectively provided at their outer ends with openings engaged by the hooks of the struts, one of the struts 55 engaging the stress applying member and the other bearing on the closure cap.

In testimony whereof I affix my signature.

JOSEPH TAYLOR.
